(57) **CLAIM**

The ornamental design for softball pitching tunnel, as shown and described.

DESCRIPTION

FIG. 1 shows a top front perspective view of an embodiment of a softball pitching tunnel showing our new design; FIG. 2 is a front elevation view thereof, with a rear elevation view thereof being a mirror-image of the front elevation view;

FIG. 3 is a right elevation view thereof;

FIG. 4 is a left elevation view thereof;

FIG. 5 is a top elevation view thereof; and,

FIG. 6 is a bottom elevation view thereof.

The line shading on the softball pitching tunnel depicts flat surfaces.
